UNITED STATES PATENT OFFICE

WALTER L. FRY, OF SCARSDALE, NEW YORK, ASSIGNOR, BY MESNE ASSIGNMENTS, TO
WIL-FRY CORPORATION, OF NEW YORK, N. Y., A CORPORATION OF DELAWARE

SEAT COVER

Application filed December 5, 1927. Serial No. 237,602.

My invention relates to improvements in seat covers, such as are placed over the back rests and seat portions of various seats and particularly the seats of motor cars and the like, and the object of my invention is to produce a seat cover which can be easily applied to cover the front and back of the back rest of the seat, which will also cover the seat portion and will lie without wrinkling and make a smooth handsome cover for the seat. This particular invention is especially adapted to the type of seat having the front and back portion of the back rest exposed and it can be used to especial advantage on folding seats such as are used in motor cars between the front and back seats of the car. The seat cover is not, however, confined to this particular use and is suited for any seat having the back rest with both front and rear exposed.

My invention is also intended to produce a cover in which the back portion which covers the back rest will extend beneath the back rest and connect with the seat cover so that the back rest will have a proper cover on the back side, and this will serve to tension and hold in place the seat cover proper and resist the tendency of this part of the cover to work forward and to become wrinkled.

My invention also contemplates having the front part of the cover for the back rest connected over the top of the back rest of the back part of this cover and this back portion will therefore have a tendency to prevent displacement of the front part and to prevent the front part of the back rest cover from working down and being displaced.

In the preferred embodiment of my invention, I have the front cover part of the back rest connected to the back cover part of said back rest, as above described, and have the lower part of the back rest cover back connected to the seat cover so that in such case the back cover portion of the back rest serves as a tension and regulating element connecting the front cover part of the back rest and the seat cover, and thus the said back part of the cover lying behind the back rest will resist the tendency of the front part of the back rest cover to work down and become

distorted, and also will resist the tendency of the seat cover to likewise become displaced.

I also prefer to connect the front and back portions of the back rest cover at the edges so as to form a casing or slip open at the bottom, which can be slipped on over the back rest and thus will completely envelope said back rest and make a very handsome cover. This arrangement does not preclude the above described connections between the several parts of the cover but rather makes such connections easier to carry out, all of which will be better understood from the description which follows:

Figure 1 is a broken perspective view showing the application of my improved slip cover to the folding seat of a motor car;

Figure 2 is an enlarged vertical section of the cover showing its application with the seat parts illustrated by dotted lines;

Figure 3 is a broken enlarged detail showing one means of connecting the back part of the cover to the seat cover proper;

Figure 4 is a detail illustrating a means of fastening the front edge of the seat cover; and

Figure 5 is a cross section on the line 5—5 of Figure 2.

The cover has one portion 10 of flexible and suitable material which is adapted to lie over and cover the front of a back rest of the seat as illustrated in Figures 1 and 2, and it connects over the top of the back rest as shown at 11 with a back section or portion 12 which lies upon the back of the back rest and is long enough at its lower edge to extend beneath it as shown at 12', where it is connected by stitching 13' or other suitable connections, with the seat cover 13 which lies upon and covers the seat proper. Obviously the parts 10, 11, 12 and 13 might be in one piece but it is more convenient to have them in connected pieces as it prevents using one exceedingly long strip of goods.

As a matter of convenience and to make the cover more handsome, I prefer to unite the side edges of the parts 10 and 12 and this can be done by attaching to the said parts side strips 14, as illustrated in Figure 5, but it will be understood that the edges of the

said parts 10 and 12 might be otherwise united so as to form the cover for the back rest into a casing, open at the bottom, which can be readily pulled on over the back rest and make 5 a very handsome cover which cannot be readily displaced by accidents but can be easily removed when desired.

I have found that it is desirable to have the member 10 unfastened at its lower edge, but 10 to prevent distortion and to keep it in place I provide a keeper or hem 15 which carries a weight 16, which can be in the form of a readily insertable or removable bar.

The part or member 13 is wide enough to 15 cover the seat proper and long enough to extend over the front edge of the seat where it can be confined in any convenient way. I have shown a preferred means of attachment in which at the front lower corners this member 13 is provided with tabs 17 having eyelets 18 therein, through which fastening elements like flexible cords 19 are passed, and these can be fastened around some convenient and accessible part of the machine, for example, 20 in Figure 1 I have shown these members 19 tied to the hinge leg 20 of the seat, but, obviously, this fastening of the front edge will depend on the various seat constructions and it can be fastened in other ways without affecting the invention.

From the foregoing description it will be seen that the cover can be very easily applied or removed. The casing formed of the parts 10, 11, 12 and 14 is pulled on over the back 35 rest of the seat, the member 13 is extended beneath the back rest and over the seat proper and the front edges secured as described, all of which can be done easily and quickly, and all parts of the cover will lie smooth and, because of the connection between the parts already carefully described, the embodied parts 10, 12 and 13 are not likely to be disturbed.

I claim:

45. 1. A seat cover comprising a casing open at the bottom and shaped to fit over the back rest of a seat, and a cover for the seat proper connected to the lower back portion of the aforesaid casing and adapted to extend beneath the back rest and lie over the seat portion of a seat.

2. A seat cover comprising a casing shaped to cover and envelope the back rest of a seat, and a cover for the seat proper connected beneath the back rest to the back part only of said casing.

In testimony whereof, I have signed my name to this specification this 1st day of December, 1927.

60.

WALTER L. FRY.
